UNITED STATES PATENT OFFICE.

REME A. BEAUSEJOUR, OF NEW YORK, N. Y., ASSIGNOR TO STANDARD VARNISH WORKS, OF NEW YORK, N. Y., A CORPORATION OF NEW YORK.

ARTICLE-HOLDER FOR LIQUID-COATING DEVICES.

1,106,915.

Specification of Letters Patent.

Patented Aug. 11, 1914.

Application filed March 29, 1912. Serial No. 687,141.

To all whom it may concern:

Be it known that I, REME A. BEAUSEJOUR, a subject of the Crown of Great Britain, and resident of the borough of Queens, in the city and State of New York, have invented a new and useful Improvement in Article-Holders for Liquid-Coating Devices, of which the following is a specification.

10 This invention relates to an article holder for liquid coating devices, and more particularly to an article holder to be used in connection with apparatus which coats articles by the dipping process.

15 The objects are to provide a device of this nature which is very simple to load and unload; which will securely retain the articles in position during the dipping process without the necessity of clamping the said articles at any point; which will accommodate itself to articles of various sizes and shapes and which is withal very simple and cheap in construction.

20 The article holder which is the subject of this invention is particularly designed for holding articles of furniture, or building equipment, such for instance, as panels or doors, etc. which are composed of hollow metal.

25 A practical embodiment of the invention is represented in the accompanying drawings in which,

Figure 1 represents a top plan view of the article holder with two articles supported therein. Fig. 2 represents a section taken in the plane of the line A—A of Fig. 1, looking in the direction of the arrows. Fig. 3 represents an end view of the parts shown in Fig. 1, and Fig. 4 represents an end view thereof.

30 The article holder comprises a framework having a pair of base members 1, 2, which may conveniently be composed of iron, extending from front to rear at each side thereof and a pair of transverse angle iron bottom members 3, 4, the member 3 being slidably mounted on the base members 1 and 2, while the member 4 is fixedly secured at each end thereto; thus the two form together an adjustable bottom support for the articles 5 and 6 which are to be coated. The device also includes a pair of upright side members 7, 8, which may also be composed of angle-iron secured to the base

members 1, 2, at the extreme rear ends 55 thereof; and a pair of upper or top members 9, 10, extending transversely from the side member 7 to the side member 8, which transverse top members 9, 10, are also composed of angle-iron.

60 A pair of braces 11, 12, are secured at an angle to the members 1, 2, and the members 7, 8, by means of short bolts 13 which engage the lower end of the braces 11, 12, and the base members 1, 2; and a through bolt 65 14 which engages the upper ends of the braces 11, 12, and passes through the side members 7, 8. These braces may also be composed of iron, preferably of flat section. The upright side members 7, 8, are provided throughout their upper halves, with a longitudinal series of closely spaced holes 15, while the transverse top members 9, 10, are each provided at their ends with holes fitted to register with the holes 15 in the 75 side members 7, 8; whereby the members 9, 10, may be secured in any desired vertical adjustment by means of suitable bolts 16 and butterfly nuts 17. The transverse top members 9, 10 are each provided with a 80 longitudinal series of holes 18, the holes in the member 10 being directly above the holes in the member 9, whereby they are adapted to receive headed pins 19 for supporting the upper ends of the articles to be 85 coated, as clearly shown in Fig. 4. The transverse bottom members 3, 4, are also constructed with a longitudinal series of holes 20 fitted to receive staples 21 for holding the lower ends of the articles to be 90 coated, as is also clearly shown in Fig. 4.

95 The article holder as a whole may be equipped with rollers 22 removably secured to the base members 1 and 2, by means of bolts and nuts 23.

100 In operation, supposing the articles to be coated to be, for instance, hollow metal doors; battens 24 of wood or other convenient material are secured to the upper and lower edges of the doors, the said battens being both wider and longer than the edges of the doors. The doors are then placed in the article holder, while the latter is in its vertical position on its rollers 22, as clearly shown in Figs. 2 and 3, the doors 105 resting upon the bottom members 3, 4. The pins 19 are then dropped into the appropriate holes 18, so that one pin will engage

each side of the rearwardly protruding ends of the upper battens 24, and the staples are also dropped into the appropriate holes in the bottom members 3, 4, so that they engage each side of the lower battens 24. It will be noted that inasmuch as the pins 19 engage only the protruding ends of the battens 24, the said pins do not come in contact at all with the doors to be coated; and 10 furthermore, that the lower battens 24, being wider than the thickness of the doors, prevent the staples 21 in the bottom member 3 from coming in contact with the sides of the doors; while at the same time the battens protect the upper and lower edges of the doors from being coated with varnish. After the articles, of the desired 20 number, have been locked in the article holder, the latter may be wheeled to the dipping tank, and picked up by the bracket or crane, (not shown) for performing the dipping operation. The bracket or crane should be provided with cables, straps or other devices for engaging the sides of the 25 article holder at the ends of the bolts 13, 14, in order that the article holder may be supported at the said points and hence tilted backward as it is lifted from the floor in order that the articles to be coated may 30 rest against the through bolt 14 and top member 9, thus obviating the possibility of the articles falling forward out of the holder, while also insuring that the articles are held at the proper angle for dripping. 35 It will be understood, of course, that the rollers 22 may be removed before the dipping operation is performed.

The article holder above described provides means for securely supporting the 40 articles to be dipped without engaging any part of the article which should be coated; while the said article holder may be very quickly and easily loaded and unloaded without the necessity of tools or complicated operations.

It is to be understood that various changes might be resorted to in the form, construction and arrangement of the several parts without departing from the spirit 50 and scope of my invention, hence I do not wish to limit myself strictly to the construction herein set forth, but

What I claim is:

1. An article holder of the character described comprising a framework having a 55 pair of top members, a pair of bottom members, and devices arranged to slidably fit

in said top and bottom members for holding the articles in position in the holder.

2. An article holder of the character described comprising a framework having a pair of top members, a pair of bottom members, a single set of devices arranged to slidably fit in the pair of top members and two sets of devices arranged to slidably fit in the pair of bottom members, the said devices being adapted to hold the articles in position in the holder. 60 65

3. An article holder of the character described comprising a framework having a pair of top members in one plane, a pair of bottom members in another plane, and devices arranged to slidably fit in said members for holding the articles in position in the holder. 70 75

4. An article holder of the character described comprising a framework having a pair of adjustable top members, a pair of bottom members and devices arranged to slidably engage said members for holding the articles in position in the holder. 80

5. An article holder of the character described comprising a framework having top and bottom members, pins arranged to slidably engage the top members and staples arranged to slidably engage the bottom members, the said pins and staples serving 85 to hold the articles in position in the holder.

6. An article holder of the character described comprising a framework having a pair of adjustable top members, a pair of bottom members one of which is movable toward and away from the other, and devices arranged to slidably engage said members for holding the articles in position in 90 95 the holder.

7. An article holder of the character described comprising a framework having a pair of adjustable top members in one plane, a pair of bottom members in another plane, one of said bottom members being movable toward and away from the other, and devices arranged to slidably engage said members for holding the articles in position in 100 105 the holder.

In testimony, that I claim the foregoing as my invention, I have signed my name in presence of two witnesses, this twenty-eighth day of March 1912.

REME A. BEAUSEJOUR.
